CLAIM

The ornamental design for a housing for a riflescope eyepiece and reticle, substantially as shown and described.

DESCRIPTION

FIG. 1 is a front and side perspective view of a housing for a riflescope eyepiece and reticle showing my new invention;

FIG. 2 is a side elevational view thereof, the two sides of the housing being symmetrical, with the housing being shown in operative relationship with a riflescope illustrated in broken lines;

FIG. 3 is a top plan view thereof;

FIG. 4 is a bottom plan view thereof;

FIG. 5 is a rear view of the eyepiece end thereof; and FIG. 6 is a front view thereof.

The broken-line portion of FIG. 2 is only illustrative of a typical riflescope with which my housing may be used, and is not a part of the design claimed.
